[57] **CLAIM**

The ornamental design for a dolly, as shown and described.

DESCRIPTION

FIG. 1 is a front perspective view of a dolly showing our new design;

FIG. 2 is a right side elevational view thereof, the left side elevational view being a mirror image of that shown;

FIG. 3 is a top plan view thereof, the broken lines being for illustrative purposes only;

FIG. 4 is a front elevational view thereof;

FIG. 5 is a bottom plan view thereof; and

FIG. 6 is a rear elevational view thereof.

FIG. 1.

FIG. 2.

FIG. 3.FIG. 4.FIG. 5.FIG. 6.
